BABY GARMENT

Margaret Collins, Bayonne, N. J.

Application June 29, 1932. Serial No. 619,827

2 Claims. (Cl. 2—111)

This invention relates to baby garments and it particularly relates to a so-called three-in-one garment in which the shirt and the stockings are adapted to be combined with a diaper folded in a fashion to serve as breeches, the object of the invention being to provide means to clothe an infant without having to resort to safety pins to fasten the garments together.

It is also an object of the invention to provide means to clothe an infant, which means will not be liable to be torn by the stitches of the safety pins, or other similar fastening means and to thereby relieve the mother of a great deal of anxiety lest her infant child might hurt himself by playing with a safety pin he disengaged, and to furthermore relieve her of a great amount of work keeping the garments in proper repair.

It is also an object of the invention to provide means to clothe an infant in such a manner that he is always fully clothed, that no part of the clothing can be pushed off so as to lay bare parts of the body and to expose the infant to the danger of catching cold.

It is another object of the invention to provide means to clothe an infant, which means can easily be washed because they are free of any metal parts which might rust and discolor the garment and might happen to press upon the body of the infant.

It is also an object to provide means to clothe an infant, which means can be produced at a reasonable cost and will give a pleasing and attractive garment for the infant so as to be a source of economy and pleasure for the mother.

With these and other objects in view, which will be more apparent from the following description, reference is had to the accompanying drawing, in which

Figure 1 is a perspective view of an infant clothed with the three-in-one garment forming the subject matter of my invention;

Figure 2 is a front elevation of a shirt forming a part of the three-in-one garment, one front part of the shirt being turned up so as to show the manner in which certain fastening means are secured to the shirt;

Figure 3 is a front elevation of a diaper and shows how the same is folded and tied to serve as breeches for the infant, a system or series of apertures being shown together with fastening means by which the breeches, shirt and the stockings are fastened together so as to make one complete garment;

Figure 4 shows the rear side of the diaper folded and fully tied into breeches;

Figure 5 shows one of the stockings, one side of the stocking being cut into and the flap thus formed being turned down to show the apertures by which the stockings are tied to the breeches;

Figure 6 is a top view of the breeches if the front part of the same, as shown by Fig. 3, is turned 180° so as to flatten out the breeches into one single strip of cloth.

Like numerals denote like parts throughout the various figures.

Referring now to the drawing the numeral 10 denotes the shirt, forming a part of the three-in-one garment, 11 the front and 12 the rear part of the shirt.

Strings 13, made of a relatively narrow twist-less tape, are secured to the shirt, suitably by stitches made by hand or machine, at about the middle of the string so that the two equally long ends of tape thus become available and may be tied into knots when the garment is put together. 70 Such strings 13 are provided on either side of the front part of the shirt, preferably at its middle, and likewise at corresponding places on its rear part, though the Figure 2 shows only one string 13 for each part of the shirt. From an inspection 75 of Figure 2, it will, however, be noticed that the shirt is reinforced by a strip 14 of strong but soft material where the strips 13 are secured to the shirt 10.

The stockings 15 are provided on both their 85 outer sides, near their upper rim, with two apertures 16a and 16b on the one side and 16c and 16d on the other, which apertures may have the form of a slot in the nature of a button-hole, either in vertical or horizontal direction or in the form of 90 annular holes, or of any other suitable form.

According to my present experience I have found that apertures 16 of vertical direction answer the purposes of my invention very well and, therefore, whenever I refer to similar apertures, 95 I always mean that they suitably are of vertical direction, even though annular or horizontal apertures answer as well. The apertures 16 in the stocking are located directly opposite to each other and to make them serviceable, they are 100 also reinforced by a strip 17 of strong but soft material.

As to the breeches, I wish to say that they are formed by a rectangular diaper or strip 18 of material of the double length of the body measured 105 downwardly from its middle. An inspection of Figure 6 will show that the diaper 18 is provided with two systems or series of apertures across the width, one near and parallel to each of the edges 19 and 20.

65

85

90

95

100

110

The edge 19 is the upper edge of the front part F of the breeches and 20 the upper edge of its rear part R.

By an inspection of the Figure 3, which shows 5 the diaper 18 folded up at its middle line m (see Figure 6), it will be noticed by the dotted line 21 that the narrow strips 22 along the sides of diaper 18 from the edge 19 to the middle line m, are tucked in and that there are no apertures 10 similar to apertures 16 in the stockings 15, in said flat strips 22 of the front part F. By tucking in these strips 22 on both sides of the front part F and then folding up the diaper 18, we notice 15 that the sides of the rear part R project from below the front part F and form the flaps 24, of which the Figure 3 shows the one at the left side in its projecting position, whereas that on the right side is tied upon the front side F.

While the strips 22 of the front part F have 20 no apertures at all, we notice that the corresponding parts of the rear part R or flaps 24 are provided near the edge 20 with certain series of apertures so for instance with apertures 25 and 26 on the left side and with apertures 27 and 28 25 on the right side (see Figure 6). Furthermore we find that near the middle line m, there are provided on the left side, the apertures 29 and 30 and on the right side the apertures 31 and 32. From an inspection of Figures 3 and 6 it 30 will be apparent that the pairs of apertures 25, 26—29, 30—27, 28 and 31, 32 are arranged spaced- 35 ly symmetrically to each other and that the distance between the apertures of each pair is the same.

35 In linear arrangement with the apertures 25, 26 and 27, 28, there are provided two other pairs of apertures 33, 34 and 35, 36, each pair being located equidistantly from the longitudinal center line of the diaper 18.

40 In approximately the middle between the apertures 25 and 33 there is provided a single aperture 37 and similarly on the other side the aperture 38 between the apertures 36 and 27.

Between the apertures 25 and 37 a tape 39 is 45 secured, suitably by stitches, with one of its ends to the rear part R closely to aperture 25 and likewise a tape 40 on the other side closely to aperture 27 between the apertures 38 and 27.

Similar tapes 41 and 42 are secured to the rear 50 part R inwardly from and closely to apertures 29 and 31, respectively.

In the front part F there are also two lines 55 of apertures which are in symmetrical arrangement to each other along the longitudinal center line of the diaper 18 and are equidistantly arranged from the alinement of apertures in the rear part R which they will cooperatively engage as described below. So the series or pairs of apertures 43, 44 and 45, 46 have their counter part 60 in two pairs of apertures 47, 48 and 49, 50 on the right side of the front part F and are alined in the same distance from the middle line m as the line of aperture 30—32 of the rear part R.

65 Another line of apertures runs parallel to the edge 19 of the diaper 18 and comprises two pairs of apertures 33', 34' and 35', 36' located oppositely and symmetrically to the pairs of apertures 33, 34 and 35, 36.

70 On each side of the front part F and in alinement with the apertures 33'—36', there are provided two pairs of apertures arranged equidistantly from each other and aforesaid line of apertures, there being also the same distance between the individual apertures of each of these pairs as 75 in any other pairs of apertures mentioned before.

At the left of aperture 33' there are the apertures 51, 52 and 53, 54 and at the right of aperture 36' there are the apertures 55, 56 and 57, 58 (see Figure 6).

From Figure 3 it is apparent that on the outside 80 of the front part F of the breeches there are provided two strings or tapes 59, one on each side of the breeches and symmetrically arranged to each other. They are secured to the breeches and reinforced at their place of attachment in the same 85 fashion as the tapes 13 are secured on the shirt.

In Figure 6 these tapes 59 appear in dotted lines.

On the inside of the front part F, therefore appearing in Figure 6 in full line, the tape 61 is secured with one end between the apertures 44 and 45 and similarly the tape 62 between the apertures 47 and 48; likewise the tape 63 is secured between apertures 52 and 53 and the tape 64 between the 90 apertures 56 and 57.

Having now fully described the various elements and parts of the baby garment, I may now describe the various steps of folding the breeches and joining the shirt and stockings to the same.

First I tuck in the strips 22 on each side of the 100 front part, about as far as indicated by the dotted line 21 in Figure 3; then I fold the diaper 18 until the edge 19 falls in line with the edge 20 and the strips 24 project as is also indicated by Figure 3. Then I insert tape 39 through aperture 105 25, then tape 63 first through aperture 52 and then through aperture 26, whereupon I tie the tapes 39 and 63 as indicated by Figure 3 in its upper right corner with respect to tapes 40 and 64.

I proceed then in the same way with the tapes 41 and 61; the tape 41 is inserted through the aperture 29, the tape 61 through the aperture 44 and then through aperture 30; this is shown on the right side in regard to the tapes 42 and 62, 110 the tape 42 having been inserted through aperture 31 and the tape 62 first through aperture 49 and then through aperture 32, the ends of tapes 62 and 42 being shown ready to be tied. However, this position shown by Figure 3 with respect to 120 the tapes 62 and 42 gives me a chance to secure the stocking 15 to the breeches. To do so I introduce the right end of the tape 59 first through the aperture 16a and then through the aperture 16b, whereupon I then can tie the two ends of tape 125 59; thereupon I introduce the tape 62 first through aperture 16c, then through 16d and tie then tapes 62 and 42 as indicated by Figure 1. As to the stocking 15 for the other leg of the baby I, of course, also proceed as described above.

To combine the shirt 10 with the breeches, I insert the lower end of the shirt into the breeches until the stitches, by which the tapes 13 are secured to the shirt 10, come in line with the lines of the apertures of the front and rear of the 135 breeches. Then I insert the left end of the tape 13, on the left side of the shirt, through the aperture 33' and its right end through the aperture 34' and tie then the ends of the tape 13. The same is done with the tape 13 on the right side of 140 the shirt in connection with the apertures 35' and 36' and in the rear with both tapes 13, one of said tapes in connection with apertures 33 and 34 and the other in connection with apertures 35 and 36.

It is one of the desirable features of my invention that the garment is adjustable to the size of the infant. The garment described herein is intended for an infant of 1-1/2 years of age, but the garment may easily be adapted to fit a baby 150

only a few months old as well as for an infant of a much larger size.

In case the garment has to fit an infant of larger size, I can adjust the size of the garment by introducing the tape 63 first through aperture 51, instead of 52, and then through aperture 26, thereupon tying the tapes 39 and 63 together. As I can do exactly the same on the other side, it is obvious that I gain a considerable increase in the width of the garment.

If the infant is so small that the garment as described would be too wide, I can adjust the width of the same by further tucking in the strips 22 so that the line 21 would, at the top, move nearer to the aperture 53, or 54, and below, nearer to the aperture 45, or 46. Instead of introducing, as described above, the tapes 63 and 61 through the apertures 26 and 30, respectively, I first introduce the tape 63 through aperture 53, or if necessary through aperture 54, and tape 61 through aperture 45, eventually through aperture 46, then tuck in further the strip 22, and introduce then the tape 63 through aperture 26, then tie tapes 39 and 63, and insert the tape 61 through aperture 30, whereupon the tapes 41 and 61 are tied. When the same procedure has been followed on the other side of the garment for either widening or narrowing it, the infant will be comfortably and neatly dressed.

30 The garment may be made of any material of which diapers are generally made to keep an infant warm enough.

Finally I wish to say that the above described ways of adjusting the width of the garment are not the only ways, but that there are others, for instance, I may lay the upper left corners of the rear part R upon the front part F so that the aperture 26 registers with aperture 52 and the aperture 25 with aperture 51, whereupon I sling tape 63 first through aperture 52 and introduce

it from the rear through aperture 26, whereupon I tie tapes 39 and 63 together.

I may also put, for instance, the upper left ends of the front part F and of the rear part R together so that aperture 35 registers with aperture 25 and 54 with 26; I can then introduce tape 39 through 53 and from the rear through aperture 54 straight through aperture 26, then I introduce tape 63 through aperture 52, from the rear through aperture 51 and straight through aperture 37, whereupon I tie tapes 39 and 63. Some other variations may easily be made as the conditions may require.

What I claim is:

1. A baby garment, consisting of a shirt, having a plurality of tape like fastening means secured to its front and rear side, a diaper, having a plurality of serially aligned apertures arranged parallel across its width both near and intermediate its front and rear edges, and tape-like fastening means on the inner and outer side of said diaper, and a pair of stockings, each stocking having a plurality of apertures engaging the aforesaid tape like fastening means.

2. A baby garment, consisting of a shirt, having a plurality of double ended tape-like fastening means symmetrically secured to its front and rear side, a diaper, having a plurality of serially-aligned apertures arranged parallel across its width both near and intermediate its front and rear edges, tape-like one ended fastening means on the inner side of the diaper, and tape-like double ended fastening means on its front end, and a pair of stockings, each stocking having a plurality of oppositely arranged pairs of apertures engaging the inner and outer fastening means secured to the diaper at its side intermediate its front and rear edges.

MARGARET COLLINS.
